UNITED STATES PATENT OFFICE.

JOHN ROY, OF NEW ORLEANS, LOUISIANA.

PILE-DRIVER.

SPECIFICATION forming part of Letters Patent No. 278,603, dated May 29, 1883.

Application filed December 18, 1882. (No model.)

To all whom it may concern:

Be it known that I, JOHN ROY, a resident of the city of New Orleans, parish of Orleans, and State of Louisiana, have invented a certain new and useful Improvement in Pile-Drivers; and I do hereby declare the following to be a full, clear, and correct description of the same, reference being had to the annexed drawings, making a part of this specification.

10 This invention relates to certain improvements in pile-driving machines; and it consists in a combination, with the main frame thereof, of a tramway and movable leads, whereby all the piles in a bent can be driven perpendicularly or at an angle without moving the machine.

20 My invention further consists in the combination of parts and the details of construction, hereinafter more fully described and specifically claimed.

In the accompanying drawings, Figure 1 represents a front elevation of my machine, and Fig. 2 a side view of same.

The letter A designates longitudinal timbers, 25 secured at requisite distances apart by having cross-timbers B bolted or otherwise secured thereto, so as to constitute the lower part of the machine. The timbers A are preferably arranged in pairs and mounted on wheels c, so 30 as to enable the same to be moved in a forward or backward direction. Sectional frames are erected at and near the forward end of the timbers A, as shown at D E. These sections are properly strengthened by means of braces, 35 and are connected at their upper ends by longitudinal side timbers, F, from which the diagonal braces extend downwardly and rearwardly, as shown at G H. The frame is furthermore strengthened by chains or rods i i', 40 which extend fore and aft from the upper part of the sectional frame E to the outer corners of the lower frame, as shown.

Across the forward ends of the upper timbers, F, is constructed a tramway or pair of rails, K K, on which operates a pair of wheels, l l', that are fitted so as to revolve with an axle, or on pins m m' connected with a block, N, forming the head of the leads O, the sides of which are secured at requisite distances 45 apart by braces a and an adjustable box, b, the latter connected to the leads by bolts, and

50 to the lower front timber, B, by bolts, stirrups, or other means which will admit of the same being quickly released whenever it is required to move the leads to the right or left of the frame. The leads are moved in either of the aforesaid directions by means of ropes or chains p p', which are connected with the opposite ends of the head-block N, and which pass over sheaves q q' at the ends of the tramway, from whence they pass downwardly to windlasses R R' in the lower part of the front sectional frame, as shown.

The boiler and operating machinery is mounted in the rear end of the lower part of the frame, thus serving to properly balance and hold the frame in position.

An attachment for sawing and trimming the piles is also connected with my machine; but as this part may form the subject of another application no further reference is herein made to the same; nor is it deemed necessary to particularly refer to the hoisting mechanism shown, as said mechanism is common in all pile-driving machines.

75 From the above description it will be seen that the leads can be moved to the right or left or held in a diagonal position, as the nature of the work may require.

Having described my invention, what I claim 80 as new, and desire to secure by Letters Patent, is—

1. The combination, in a pile-driver having a frame provided at its top with a tramway, of the adjustable leads suspended from a wheel- 85 axle or pivots, so that the piles may be driven perpendicularly or at an angle, as described.

2. In pile-driving machines, a frame composed of timbers A and B, having vertical sectional frame D and E, secured thereto, as described, and the said frames surmounted by a tramway, K, in combination with the movable leads O, devices for securing them to the frame B, and operating mechanism, substantially as 90 and for the purpose specified.

95 In testimony whereof I affix my signature in presence of two witnesses.

JOHN ROY.

Witnesses:

J. N. MÜLLER,
P. J. FINNEY.
